UNITED STATES PATENT OFFICE.

HARRY BLOOD, OF MILWAUKEE, OREGON.

POCKET TOILET SET.

Application filed November 14, 1922. Serial No. 600,926.

To all whom it may concern:

Be it known that I, HARRY BLOOD, a citizen of the United States, and a resident of Milwaukee, in the county of Clackamas and 5 the State of Oregon (having his post-office address at box 78 R. F. D. No. 1, in said city and State), have invented a new and useful Pocket Toilet Set, of which the following is a specification.

10 My invention relates to an improvement in a pocket toilet set and a case for the same wherein all of the necessities that a man finds the need of in his daily requirements, or when he is away from home or his place 15 of abode, the same being arranged in a highly compact form and arranged in a case and the closure for the same in such manner that when the closure is made shut the whole is encased in so compact a form 20 as to permit the whole to be carried in the pocket.

I attain these results by the article illustrated in the accompanying drawings, in which—

25 Fig. 1 is a plan view of the set, in place in the case with the closure of the same shown in open position, and each of the articles in place in which they are secured by means later to be described. Fig. 2 is a partial 30 cross section through the lower part of the case and is made to show the method of making the different articles fast to the case. Fig. 3 is a partial cross section through the case and is made to illustrate the method of 35 fastening the closure and the case in place when shut and in locked position. Fig. 4 is a partial cross section of the case showing how the closure is secured to the case by hinged means, and Fig. 5 is an end view of 40 one of the containers for holding the toilet materials showing the closure for controlling the emission of the toilet material therefrom.

Similar letters and numerals refer to similar parts throughout the several views.

45 1 is the case and 2 is the closure which is hinged to the case about pin or rod 3 in the usual manner. On the opposite edge of the case from the hinged edge is a push button 4 which is secured to a spring attachment 5 which in turn is held to the case by rivet 6. When the closure is shut the spring member 5 is sprung into the dotted position as shown in Fig. 3 until the notch 7 passes 50 over the lip 8 and engages the catch, in which condition it remains until it is desired

to open the closure, at which time a pressure is exerted upon the push button 4 which disengages the spring latch and the closure is permitted to be opened. 8^a is the razor 60 which is placed in position within the case in a compartment provided for that purpose within the case, 9 is the styptic pencil which is held in position by spring clamp 9^a which is secured to the case, and 10 is a cake of 65 shaving soap which is also in a compartment provided in the case for maintaining the same in position, 11 is the handle for the razor which is held in placement by spring clamp 11^a, 12 is the shaving brush which 70 is held in place by spring clamp 12^a, 13 is a container for the shaving powder which is held in placement by means of spring clamp 21 which is preferably made of one 75 piece and is so arranged and made into a shape as to clamp tooth brush 14, tooth powder holder 15 and toilet water container 16 in position within the case, 17 is a pair of tweezers which are held in position by means of spring clamp 17^a, 18 is a nail file 80 which is held in position by means of spring clamp 18^a and 19 is a comb which is held in position by means of spring clamp 19^a, and 20 is a pair of scissors which are held in position by spring clamp 20^a each of the 85 spring clamps are secured to the case of the closure by rivets, by spot welding or by other suitable means to permit the finishing of the same on the exterior of the case in a smooth and workmanship like manner, and 90 the whole case is when finished of a very compact form and easily accessible to the pocket of the wearer or user. In order that the case may be maintained in a sanitary manner, at all times, and that no disease 95 germs may be developed or cultures started, in the various utensils, or within the case itself, I have provided a medicated means provided to be maintained within a case and the fumes given off from the medicated matter contained will kill and otherwise prevent 100 the development of germ life within the case, this is shown by a case or box 23, which may be placed within the case or secured to the closure, 24 would be the medicated material placed within the box 23, and 25 would be perforations to permit the escapement of 105 the medicated fumes from the case or box 23 and during the period when the closure of the pocket toilet set was closed, these 110 medicated fumes would permeate the whole of the inner portion of the pocket toilet set

and prevent the development or growth of life within the case or the contents of the same.

Having thus described my invention I wish to make the following claims therefor:

- 5 1. In a device of the class described, a case having a bottom and hinged cover, a transverse partition disposed adjacent one end and subdivided to provide a series of 10 transverse end compartments, a pair of transversely alined spring clips arranged adjacent the cross partition, and a single spring clip extending longitudinally of the bottom designed for separately retaining a 15 plurality of articles the longitudinally extending spring clip being formed of resilient material having well defined base portions flatly engaging the bottom of the case with intermediate portions of the strip bent 20 upon themselves to form double walled resilient clip arms, and said double walled clip arms being outwardly curved intermediate their upper and lower ends adapted for clipping and retaining curved articles.
- 25 2. In a device of the class described, a case having a bottom and hinged cover, a transverse partition disposed adjacent one end and

subdivided to provide a series of transverse end compartments, a pair of transversely alined spring clips arranged adjacent the 30 cross partition, a single spring clip extending longitudinally of the bottom designed for separately retaining a plurality of articles, the longitudinally extending spring clip being formed of resilient material having well defined base portions flatly engaging the bottom of the case with intermediate 35 portions of the strip bent upon themselves to form double walled resilient clip arms, and said double walled clip arms being outwardly curved intermediate their upper and lower ends adapted for clipping and retaining curved articles, and a closure latch including a spring arm secured to the bottom and having an opening therein adapted to 40 receive a struck out lug carried by the cover.

In testimony that I claim the foregoing as my own I hereunto attach my signature in the presence of two witnesses.

HARRY BLOOD.
